UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

AUTOMATICALLY-THREADING LOOM SHUTTLE.

Application filed September 27, 1928. Serial No. 308,724.

This invention relates to automatically threading loom shuttles wherein the filling supply in the shuttle is changed from time to time.

It is now the ordinary practice in weaving with automatic looms of the filling replenishing type to provide a series of filling carriers with wound filling thereon and contained in a hopper or supply. The ends of the filling are usually secured to some fixed part, so that on the first pick of the shuttle following replenishment the shuttle will become partially threaded and on the return pick of the shuttle to the filling replenishing shuttle box it will usually become fully threaded. It may happen at times during the weaving operation, also, that the filling thread may be thrown out of the side delivery eye and the shuttle become partially unthreaded.

In order that perfect cloth may be woven, the filling that is delivered from the shuttle should be maintained under uniform tension, but since the filling thread does not lead through the side delivery eye of the shuttle on the first pick following replenishment, and is liable to be thrown out of the side delivery eye during weaving, tension on the thread is liable to vary, being less when the thread is not delivered through the side delivery eye.

An important feature of the present invention consists in providing an automatically threading loom shuttle with means to insure uniform tension on the thread whether it be delivered through the side delivery eye or not. More specifically stated, the present invention provides a thread tension device preferably adjacent the entrance of the longitudinal thread passage and a hook which extends downwardly into the thread passage from the top thereof, and is provided at its lower portion well down in the longitudinal passage with a thread leading eye below the top of the tensioning device so that both runs of the thread may be directed through the tensioning device when the shuttle is partially threaded to thereby compensate for the loss of tension usually exerted upon the thread when delivered from the side delivery eye.

The invention and novel features thereof will best be made clear from the following description and the accompanying drawings of one good form thereof.

In the drawings:

Fig. 1 is a plan view of an automatically

threading shuttle containing the present invention and showing more particularly the thread delivering end of the shuttle;

Fig. 2 is a detached perspective view of a threading block provided with the present invention and showing both leads of the thread passing through the tension device when the shuttle is partially threaded;

Fig. 3 is an enlarged section on the line 3—3 of Fig. 1; and

Fig. 4 is a longitudinal section of the threading block.

The shuttle 1 is provided with the usual side delivery eye 1^x and bobbin chamber 2 in which a filling carrier 3 containing the supply of filling is detachably mounted. The detachable mounting of the filling carrier or bobbin 3 is not herein shown because it forms no essential part of the present invention and may be of the usual type of bobbin holding jaws.

Frontward of the bobbin chamber the shuttle is provided with a threading block receiving recess in which the threading block 4 is mounted and in which it is held by the usual cross-bolt passing through an opening 5 of the block.

The threading block 4 is provided with the longitudinal thread passage 6 and at the entrance portion of the thread passage is a thread tensioning device, which, in the present instance of the invention, comprises the two tensioning members 7 and 8 which may be appropriately mounted in the threading block at the entrance portion thereof by a pin 9 permitting movement of the tensioning members towards and from each other.

The tensioning members 7 and 8 extend upwardly and the upper ends thereof are flared outward at 10 and 11. The front wall 12 and the back wall 13 of the threading block have each a socket or recess 14 in which the outwardly flared upper end portions of the tensioning members may be received, as indicated in Figs. 2 and 3, the construction being such that when the filling thread is being drawn from the filling carrier or bobbin it will be guided downwardly by the upwardly and outwardly inclined end portions 10 and 11 of the tensioning members into a position between the two.

In the present instance of the invention, the threading block is provided with the seats 15 and 16, one at each side of the longitudinal thread passage, to accommodate the ten-

sioning members 7 and 8 and to also provide the recesses 14 for the reception of the upwardly and outwardly flaring ends of the tensioning members, and, as indicated more clearly in Fig. 3, the open sockets or seats 14 have their upper edges 17 slightly above the outwardly flaring ends of the tensioning members, to thereby insure that the filling thread may not catch on the tensioning members as it is directed between them.

In accordance with the present invention, the tensioning members are under the influence of spring means for normally holding them in their tensioning position, and, as shown in the present instance of the invention, a spring 18 which is seated in a recess 19 of the threading block bears upon the tensioning member 7, while the opposing tensioning member 8 rests against the end of a threaded adjusting bolt 20 which passes through the back wall 13 of the threading block and is threaded into a block 21 with respect to which it may be adjusted lengthwise by turning the bolt. The bolt may be conveniently turned by an instrument engaging the slot 22 of the bolt and a locking nut 23 may be provided to hold the parts in adjusted position. From the construction thus far described it will be apparent that the present invention contemplates a thread tensioning device preferably of the spring clamp type at or adjacent the longitudinal thread passage 6, to act upon the thread during weaving and to impart the requisite tension thereto.

At the forward end of the thread passage 6 is the bridge 24 over which the thread passes on its way to the side delivery eye. The bridge 24, in the present instance of the invention, is shown as formed of vitreous material and the filling thread which passes over the bridge dips down under the arch 25 of the threading block on its way to the side delivery eye.

Exetending downwardly in a curved direction into the longitudinal passage 6 of the threading block from the front wall thereof is a hook 26, the lower portion of which is provided with a thread leading eye 27 opening upwardly, and the end portion of the hook 26 within the longitudinal passage reaches frontwardly at 28 preferably over the bridge 24, as more clearly indicated in Fig. 4.

The thread leading eye 27 opens upwardly as at 29 and is formed between the bulge 30 on the frontwardly reaching portion of the hook and the downwardly curved edge portion 31 of the hook, the construction being such that the thread leading eye is well down in the longitudinal thread passage and below the top of the thread tensioning device hereinbefore described, with the result that should the thread be not delivered from the shuttle through the side delivery eye as the

shuttle is picked, it will engage the frontwardly reaching portion 28 of the hook, and ride over the bulge 30 thereof into the upwardly opening eye 27, which being below the top of the tensioning device will maintain the supply portion *a* of the thread under control of the tensioning device and will likewise cause the delivering portion *a'* of the thread to be directed into the control of the tensioning device.

During normal weaving operations the thread will pass through the tensioning members of the tensioning device longitudinally of the thread passage, over the bridge 24, under the arch or guide 25 of the threading block and be delivered from the side delivery eye. This lead of the thread during normal weaving will cause it to be tensioned by the tensioning device and also by its tortuous course over the bridge laterally to the side delivery eye, but when the shuttle fails to be fully threaded, the tensioning effect of the bridge and tortuous lead of the thread to the side delivery eye is, of course, lost and to compensate for this loss of tension, the thread leading eye 27 of the hook 26 directs the delivering portion of the thread, as *a'*, as well as the supply end *a* through the tension device, with the result that the lost tension due to the tortuous course of the thread to the side delivery eye is compensated by both leads of the thread passing through the tensioning device, thereby insuring uniform tension on the thread whether the shuttle be fully or only partially threaded.

What is claimed is:

1. An automatically threading loom shuttle having a longitudinal thread passage and side delivery eye, a thread tension device adjacent the entrance to the longitudinal thread passage, an intermediate hook extending downwardly from the top of the thread passage between the tension device and exit end of the thread passage and provided at its lower portion with a thread lead below the top of the tension device and positioned so that a partially threaded thread will loop about the hook in a manner to cause both the forward and return runs of the thread to be directed through the tension device to maintain substantially the same uniform tension on the thread as when the shuttle is completely threaded.

2. An automatically threading loom shuttle having a side delivery eye and a threading block provided with a longitudinal thread passage, a tension device mounted in the threading block adjacent the entrance to the thread passage, a hook curved downwardly from the top of the block into the thread passage between the tension device and side delivery eye and having at its lower end a thread lead for engaging the thread when it fails to be delivered from the side delivery eye and positioned so that the partially

threaded thread will loop about the hook in a manner to cause both the forward and return runs of the thread to pass through the tension device to compensate for the loss of tension normally exerted by the delivery of the thread from the side delivery eye.

3. An automatically threading loom shuttle having a side delivery eye, a threading block having a longitudinal thread passage, a spring clamp tension device mounted in the threading block at the entrance of the longitudinal thread passage, a thread leading hook curved downwardly from one side of the threading block into the thread passage and having a thread leading eye opening upwardly from the lower part of the hook within the thread passage for engaging the thread when it fails to be delivered through the side delivery eye and positioned to cause both the supply and delivery runs of the thread to pass through the spring clamp tension device to maintain uniform tension on the thread.

4. An automatically threading loom shuttle having a side delivery eye, a threading block having a longitudinal thread passage, a spring clamp tension device mounted in the threading block at the entrance of the longitudinal thread passage, a thread leading hook curved downwardly from the top of the front wall of the threading block into the thread passage and having a thread leading eye opening upwardly from the lower part of the hook within the thread passage for engaging the thread when it fails to be delivered through the side delivery eye and positioned to cause both the supply and delivery runs of the thread to pass through the spring clamp tension device to maintain uniform tension on the thread.

5. An automatically threading loom shuttle having a side delivery eye and longitudinal thread passage, a spring clamp tension device at the entrance to the thread passage, a hook extending downwardly into the thread passage forward of the tension device and reaching forward in the lower part of the thread passage, a thread leading eye at the

lower portion of the hook below the top of the spring clamp tension device and opening upwardly to engage the thread when it fails to be delivered through the side delivery eye and positioned to cause both the supply and delivery runs of thread to be subjected to the control of the spring clamp tension device to maintain substantially the same uniform tension on the thread as when delivered through the side delivery eye.

6. An automatically threading loom shuttle having a side delivery eye and longitudinal thread passage, a tension device adjacent the entrance to the thread passage, a hook curved downwardly from one side of the thread passage and having a thread lead in the lower part of the thread passage and positioned to cause both runs of the thread looped about the hook to be subjected to the action of the tension device and maintain uniform tension on the thread when it fails to be delivered from the side delivery eye.

7. An automatically threading loom shuttle having a side delivery eye and longitudinal thread passage, a tension device adjacent the entrance to the thread passage, a bridge at the exit end of the thread passage, and a hook extending downwardly into the thread passage and positioned to cause both runs of the thread looped about the hook to be subjected to the control of the tension device when the shuttle is partially unthreaded to maintain uniform tension on the thread.

8. An automatically threading loom shuttle having a side delivery eye and longitudinal thread passage, a tension device adjacent the entrance to the thread passage, a bridge at the exit end of the thread passage, and a hook extending downwardly into the thread passage with its end reaching forwardly above the bridge and positioned to cause both runs of the thread looped about the hook to be subjected to the control of the tension device when the shuttle is partially unthreaded to maintain uniform tension on the thread.

In testimony whereof, I have signed my name to this specification.

HARRY A. DAVIS.
